PIEZOELECTRIC APPARATUS AND METHOD

Richard S. Bailey, Baltimore, Md., assignor to
Bendix Aviation Corporation, South Bend, Ind.,
a corporation of Delaware

Application August 26, 1941, Serial No. 407,615

13 Claims. (Cl. 51—165)

This invention relates to the manufacture of piezo-electric bodies, and, more particularly, to the determination of the resonant frequency of a piezo-electric body during machining operations thereon.

The phenomenon of piezo-electricity is well known in the art. Crystals exhibiting the piezo-electric effect will produce, on opposite faces, opposite electric charges when the crystal is deformed by the application of force. Conversely, application of an electric field to the crystal will result in deformation of the crystal. If an external force be applied to the crystal, and this restraint suddenly released, the crystal will snap back to its original form, executing a series of vibrations before coming to rest because of the natural elasticity of the crystal structure. The deformations resulting from these vibrations cause the appearance of an alternating potential across the faces of the crystal. The frequency of this alternating potential is, of course, equal to the frequency of mechanical vibration, and hence is directly indicative of the natural resonance frequency of the crystal. It is this latter effect, which has hitherto found little or no application, that is utilized in the apparatus and method of my invention.

Piezo-electric quartz crystals are widely employed to control the frequency of oscillators wherein great stability and precision of the output frequency is required. Several forms of oscillators of this type are described in Chapter 5 of The Radio Amateurs Handbook for 1941 as published by The American Radio Relay League. The common feature of these oscillators is an arrangement whereby electrical energy is fed to the crystal in a manner causing it continually to vibrate at its own natural frequency, and this frequency, in turn, determines the output frequency of the system.

In practice, what has been referred to as a crystal is, in reality, a small plate cut out of the mother crystal, the dimensions of which are determined by the desired operating frequency. During, and before the completion of the manufacturing processes this plate is called a blank. After completion of all operations, the finished blank is termed a crystal. In the manufacture of medium and high frequency crystals, the length and width of the blank are normally predetermined, and the natural resonance frequency of the blank is adjusted to the selected value by varying its thickness. A typical procedure for the prior art manufacture of piezo-electric quartz crystals is as follows.

A bar whose cross-sectional dimensions are equal to the desired length and width of the finished crystal is cut out of the mother crystal and a series of plates, or blanks, whose thickness is substantially greater than that giving the desired natural period is sawed out of the bar. At this stage in the operation the thickness of the blanks usually varies considerably due to the inaccuracy of the sawing operation so, a number of these blanks are then placed in a lapping machine where they are simultaneously ground by abrasion to a uniform thickness, and the thickness is then further reduced in this lapping machine until the natural period of the blanks is very slightly greater than the desired final value. During this procedure, the machine is frequently stopped and frequency measurements are made on selected blanks. The blanks are now removed from the machine and finally adjusted one at a time to the desired frequency by a hand lapping operation, the frequency being closely checked by further measurements during the hand lapping.

The control of the machine lapping operation is obviously of great importance, for if the blanks become too thin they must be discarded, and if they are removed while still too thick an excessive amount of the more expensive hand lapping is required. In either case, the cost of production is greatly increased. Two general methods, or combinations of these methods, are now used in determining when to stop the machine lapping process. In the first of them, as above stated, the lapping machine is frequently stopped, a sample blank removed, and its thickness or resonance frequency determined. It is obvious that this method materially reduces the output from the lapping machine. Further, should there be misalignment between the lapping surfaces, control of the thickness of a single sample blank does not insure that some other blank will not be lapped too thin. In the second method, the approximate lapping time is determined by use of the first method initially, and then, on subsequent lots, the total lapping time is controlled to the same value. Inaccuracies are introduced in this method by variations in speed of the lapping surfaces, and by variations in the quantity and quality of the abrasive employed. Usually, when approaching the end of the lapping period, the timing method is supplemented by the first described method. In the invention to be disclosed herein, the difficulties and shortcomings above outlined are obviated, and finished crystals may be produced in larger volume at lower unit cost, therefore:

55 One of the principal objects of my invention is

to provide method and apparatus for more economically producing piezo-electric crystals, by increasing machine output during a given period of time.

Another object of my invention is to provide method and apparatus for continuously indicating the natural resonance frequency of a piezo-electric body during a machining operation on said body, without interrupting said operation.

A further object of my invention is to provide method and apparatus obviating the close attention previously required in the processing of piezo-electric crystals.

Yet another object of my invention is to provide method and apparatus for automatically controlling a machining operation on a piezo-electric body.

A still further object of my invention is to provide method and apparatus for ascertaining a critical dimension of a piezo-electric body during a machining operation on said body.

Still another object of my invention is to provide apparatus for the interruption of a lapping operation on a piezo-electric body when the natural resonance frequency of said body reaches a predetermined value.

Other objects and advantages will in part be disclosed and in part be obvious when the following specification is read in conjunction with the drawing, in which:

Figure 1 is a diagrammatic representation of a preferred form of my invention adapted to measure the natural resonance frequency of piezo-electric crystals in a lapping machine.

Figure 2 is a graph showing a suitable transmission characteristic for the amplifier used in Figure 1. Also shown in Figure 2 is a suitable operational characteristic for the frequency meter used in Figure 1.

Figure 3 is a diagrammatic representation of an alternative form of my invention adapted to interrupt automatically the lapping process when the natural resonance frequency of the piezo-electric crystals reach a predetermined value.

Figure 4 is a graphical representation of a suitable operating characteristic for the combined amplifier and detector used in Figure 3. Figure 4, in addition, indicates the drop out current for the relay of Figure 3, to assist in the visualization of the operation of the apparatus.

In the drawing, like parts are designated by like reference characters.

Referring now in greater detail to Figure 1, a number of piezo-electric crystal blanks 5 are mounted in the work-table 1 of a lapping machine which is provided with shallow locating recesses adapted to receive and hold the blanks. The lap 2 is charged with a prepared abrasive material and rotated over the top surface of the blanks through the action of the motor 4 as transmitted by the shaft 3. Thus, the material of the blanks is gradually removed by abrasive action, and in this manner they may be reduced to any desired thickness. Operation of the machine is controlled by the line-switch 6. The above combination is well known in the art and constitutes the elements of a widely used form of lapping machine.

The motor housing is grounded at 7, thereby effectively grounding the lap 2 through the shaft 3 and the bearings (not shown) which are included as a necessary part of the lapping machine. The work-table 1 rests on the base 8 and may be insulated from ground by the presence

of an insulation barrier 9, which forms a part of the base. An amplifier 10 may advantageously be employed, and the ungrounded input terminal of the amplifier 10 may be effectively connected to the work-table 1, by direct, capacitive, or inductive coupling, while the grounded input terminal of the amplifier 10 may be effectively connected to the lap 2 through the ground 11, ground 7, motor housing 4 and shaft 3. A frequency meter 14 may be connected to the output terminals 12, 13 of amplifier 10. This frequency meter may be of the type shown, utilizing a series resonant circuit comprising inductor 15 and capacitor 17, the current through the circuit actuating radio frequency milliammeter 16 which may be calibrated in terms of the impressed frequency. The amplifier 10 may preferably incorporate an automatic gain control, maintaining the voltage applied to the frequency meter 14 essentially constant for any value of input voltage applied to the input terminals of the amplifier.

In Figure 2, curve 17 represents a suitable transmission gain vs. frequency characteristic for the amplifier 10. The frequency to which the crystals are being adjusted may lie between the central and upper portions of this characteristic. Curve 18 graphically portrays a suitable operating characteristic for frequency meter 14, the abscissa indicating the frequency, while the ordinate indicates the deflection of milliammeter 16 at that frequency, the impressed voltage being constant. The resonant circuit including inductor 15 and capacitor 17 may be preferably so adjusted that the desired crystal response frequency f_0 lies on the low frequency slope of the resonance curve 18.

In the practice of my invention, the machine lapping of the blanks may be performed in the usual manner. However, the necessity for periodic interruption of this process is now eliminated. The intermittent mechanical forces exerted on the crystal blanks during the lapping operation cause the blanks to vibrate at their own natural frequency, thereby generating piezo-electric currents of this frequency. The intimate contact existing between the crystal blank, the work-table, and the lap results in the transfer of a portion of the piezo-electric energy to the contacting surfaces, whence it is coveyed to the input of amplifier 19. Here the currents are amplified and impressed on the frequency meter 14, whereupon the output frequency is indicated by the properly calibrated milliammeter 16. Thus, by observation of the indications of the meter 16, and without any interruption of the lapping process, the operator has continuously available during the operation of the machine precise knowledge of the natural resonance frequency of the crystal blanks which are being lapped.

Referring now to Figure 3, I have shown a form of my invention adapted to automatically interrupt the lapping process when the response frequency of the piezo-electric blanks reaches a predetermined value. The lapping machine is constructed and connected to the input terminals of an amplifier in the same manner as described above. A tuned amplifier 19 may be employed, which may combine the functions of amplification and frequency determination. The output of amplifier 19 may be connected to a detector 20 which may be of the grid leak type, and in the plate circuit of this detector may be connected the latching relay 21. The contacts 22 of the latching relay 21 may be connected to interrupt the power supply connections to the motor 4.

In the relay shown, contacts 22 are normally held closed against the restoring force of the spring 23 by the magnetic effect of the plate current of the detector 20. When the plate current of the detector falls below a critical value, the contacts are opened by the spring 23 and are latched in this position by the latch bar 24 which is pivoted at 25. The contacts 22 are then held in the open position until the latch bar is manually reset by an operator.

In Figure 4, curve 25 illustrates a suitable relationship between the detector plate current and the input frequency to amplifier 19, input voltage being constant. The desired crystal frequency may preferably lie on the low frequency slope of this resonance curve. The dashed line 26 of the same figure represents the value of current at which the latching relay contacts open.

In the practice of this form of my invention, the lapping process is begun in the usual manner, and amplifier 19 is so adjusted that crystal response frequency f_0 falls on the desired portion of the resonance curve 25. The remainder of the operation is automatic, thus freeing the operator for other duties. When the frequency of the energy applied to the input of amplifier 19 reaches the desired point on the resonance curve, the plate current of detector 20 decreases to a value less than that required to maintain relay 21 in the operated position, thereby permitting contacts 22 to open and interrupt the power supply connections to the motor 4 thus terminating the lapping operation.

In view of the fact that the natural frequency of a crystal is dependent on its dimensions, it is obvious that my invention may be employed to determine any dimension affecting the natural resonance frequency of a piezo-electric crystal.

I have found that the method and apparatus of my invention may be readily employed in conjunction with harmonics of the natural resonance frequency of a piezo-electric crystal, and it is my intention that this mode of operation fall within the scope of the appended claims.

While I have described the application of my invention to the lapping of piezo-electric quartz crystals, it is neither my intention nor desire to limit the scope of my invention to this particular process or this particular material. The term "machining operation" in the appended claims is intended to describe any mechanical operation for the removal of material from a body, which produces the necessary internal stresses for the generation of alternating piezo-electric currents in that body, such as filing, milling or turning. Where reference is made to a piezo-electric substance, it is intended to describe not only piezo-electric quartz, but any substance exhibiting the piezo-electric effect, such as tourmaline or Rochelle salts.

It will be obvious that many changes and modifications may be made in the invention without departing from the spirit thereof as expressed in the foregoing description and in the appended claims:

What I claim is:

1. The method of determining the natural resonance frequency of a piezo-electric body undergoing a machining operation, which comprises measuring during the continuation of said operation the frequency of the piezo-electric currents produced in said body by the internal stresses caused by said operation.

2. The method of manufacturing a piezo-electric crystal having a predetermined response fre-

quency, which comprises the steps of moving a piezo-electric crystal blank in contact with and relative to a reducing means, amplifying the piezo-electric current generated by said motion, measuring the frequency of said piezo-electric current during the continuation of said motion, and interrupting the reducing operation when the frequency of said piezo-electric current becomes substantially equal to said predetermined frequency.

3. The process of manufacturing a piezo-electric crystal having a predetermined response frequency which comprises mechanically removing material from a blank of piezo-electric material, determining the response frequency of said blank by measuring the frequency of the piezo-electric currents generated by and during the continuation of said removal of material and interrupting the removal of material when said frequency of said current reaches a predetermined value.

4. In the process of machining a piezo-electric body, the method of determining a critical dimension of said body, which comprises measuring the frequency of the piezo-electric currents generated in said body by the internal stresses produced during said operation.

5. In apparatus for the manufacture of a piezo-electric body, the combination of a work-holder adapted to receive said body, a tool movable with respect to said work-holder, an amplifier responsive to the piezo-electric currents produced in said body by the working operation and having input terminals connected effectively to the work-holder and to the tool, and frequency indicating means connected to the output of said amplifier.

6. In apparatus for the manufacture of a piezo-electric body, the combination of a work-holder adapted to receive said body, a tool movable with respect to said work-holder, an amplifier tuned to a predetermined frequency and having input terminals effectively connected to said work-holder and to said tool, detecting means connected to the output of said amplifier, and current amplitude responsive indicating means connected to the output of said detector.

7. In apparatus for the manufacture of a piezo-electric body, the combination of a work-holder adapted to receive said body, a tool movable with respect to said work-holder, an amplifier tuned to a predetermined frequency and having input terminals effectively connected to said work-holder and to said tool, and amplitude responsive indicating means connected to the output of said amplifier.

8. In apparatus for the manufacture of a piezo-electric body, the combination of a work-holder adapted to receive said body, a tool movable with respect to said work-holder, a detector tuned to a predetermined frequency and having input terminals effectively connected to said work-holder and to said tool, and current amplitude responsive indicating means connected to the output of said detector.

9. In apparatus for the manufacture of a piezo-electric body, the combination of a work-holder adapted to receive said body, a tool movable with respect to said work-holder, and means connected to said work-holder and to said tool to determine the frequency of the alternating voltage generated within said piezo-electric body by the internal stresses produced therein as a result of and during the continuation of the working op-

eration on said body and appearing at said work-holder and said tool.

10. In apparatus for the manufacture of a piezo-electric body, the combination of a work-holder adapted to receive said body, a tool movable with respect to said work-holder, a frequency responsive device, means connecting said frequency responsive device to said work holder and to said tool, said connecting means and said frequency responsive device presenting a positive input conductance when viewed from said body, and indicating means connected to the output of said frequency responsive device.

11. In apparatus for the manufacture of a piezo-electric body, the combination of a work-holder adapted to receive said body, a tool movable with respect to said work-holder, a frequency responsive means, means connecting said frequency responsive means to said work-holder and to said tool, said connecting means and said frequency responsive means presenting a positive input conductance when viewed from said body, and means actuated by said frequency responsive means for controlling the machining operation.

12. In apparatus for the manufacture of piezo-electric crystals, the combination of a lapping machine adapted to receive a piezo-electric crystal blank, and control means arranged to interrupt the lapping process when the frequency of the piezo-electric currents produced in said blank by the internal stresses resulting from and during the continuation of the operation of said lapping machine reaches a predetermined value.

13. The method of manufacturing a piezo-electric crystal having a predetermined response frequency, which comprises the steps of reducing a dimension of a piezo-electric crystal blank by mechanical means, amplifying the piezo-electric current generated by said blank during and as a result of said mechanical reduction, measuring the frequency of said piezo-electric current during the continuation of the operation of said mechanical means on said blank, and interrupting the reducing operation when the frequency of said piezo-electric current becomes substantially equal to said predetermined frequency.

RICHARD S. BAILEY.
